UNITED STATES PATENT OFFICE

JOHN G. MUELLER, OF DAYTON, OHIO

RAIL BRACE

Application filed June 11, 1928. Serial No. 284,390.

This invention relates to a new and improved form of rail clamp and rail brace, adapted to be used in connection with the rails of a railway track.

5 It is an object of this invention to provide rail clamps and braces that are few in parts and easily and readily applied to the rails, and removed therefrom, and when so applied firmly grip the rails and hold the rails against 55

10 sliding and tilting motion.

It is also an object of this invention to 60 provide a rail brace in combination with rail clamps, and having the parts so related to each other that they can be applied to the 15 rail by a single operating means.

15 It is a further object to provide a device of this kind that may be readily applied to tracks of various gauges and rails of various sizes.

20 In the accompanying drawings there is illustrated one embodiment of the invention, but the applicant does not wish to be limited to that embodiment.

Referring to the drawings:

25 Figure 1 shows a cross section of the rails of a railway track, with the clamping means and brace attached thereto.

Figure 2 is a longitudinal section of the 30 clamping means and brace as applied to one rail.

In the drawings and in the specification like reference characters are used to designate similar parts.

The numeral 1 is used to designate the rails, 35 which are supported on the conventional tie, not here shown.

The numeral 2 represents a tie-rod having screw-threaded parts, designated by the numeral 3, on each end thereof to which the 40 clamping and bracing devices are applied.

The main element of the clamping device is more or less circular in vertical section, as is shown by the figures, and embodies a clamping member, indicated by the numeral 4, and a hook member, designated by the numeral 6.

45 Through this clamping member there is a circular opening, indicated by the numeral 5, which expands into a larger opening having vertical side walls, indicated by 50 the numeral 7. At the point where the cir-

cular opening 5 merges into the opening 7, there is formed on the clamping member an inclined face, designated by the numeral 8, which is adapted to engage with a similarly inclined face on the wedging sleeve, designated by the numeral 9. The wedging sleeve has extending therethrough, substantially in line with the opening 5, an opening indicated by the numeral 10. Through each of these openings the tie-rod 2 passes, for the purpose of holding the parts assembled to the rail.

On the wedging sleeve 9 there is an inclined surface, indicated by the numeral 11, adapted to engage with the inclined surface 8 on the clamping member to cause an upward movement of the wedging sleeve when forced against the clamping sleeve to produce a gripping action on the lower flange of the rail.

55 Fitting over the end of the screw part of the tie-rod there is a washer, indicated by the numeral 12, which has lips 13 adapted to be bent over, one to engage a surface on the wedging sleeve and the other to engage the flat surface of the nut 14. When these parts 60 engage the nut 14 and the wedging sleeve 9, the nut is held against rotation on the screw so that the parts are held in close gripping engagement with the rail.

65 The opening 10 through the sleeve 9 is oval in shape, with the long diameter thereof extending up and down, to permit free up and down movement of the sleeve on the tie-rod.

70 There has been here described one of the members adapted to grip one flange of the rail. Since each of the gripping members is of the same structure, the foregoing description is applied to each one of the gripping 75 members shown in the figures, with the exception of the gripping members on the outer flange of the rail, which are slightly modified to adapt them to the use of the brace.

80 On the outer end of the wedging sleeve 9, 85 which is applied to the outer flange of the rail, the surface is inclined for the purpose of permitting an inclined sliding motion of the brace, hereinafter described. There is also extending upwardly from the hook mem- 90

100

ber 6 a guide member, indicated by the numeral 16. This guide member 16 is adapted to fit within a groove on the brace member, hereinafter described. The brace member is composed of a piece of metal having an elongated hole in the end thereof for the purpose of receiving the end of the tie-rod. This hole is indicated by the numeral 18. The brace itself is indicated by the numeral 17.

10 The inside part of the brace member is inclined and forms an inclined bearing surface, indicated by the numeral 19, which engages the aforementioned inclined surface 15 of the wedging sleeve 9. Extending from the 15 hole 18 and toward the upper end of the brace, there is a groove, indicated by the numeral 21, adapted to receive the member 16 in such a way that the brace may slide longitudinally of the brace thereon.

20 For the purpose of holding the brace against turning there is provided a lockwasher, indicated by the numeral 22, having lips formed thereon, indicated by the numeral 23, which are adapted to be bent down to engage 25 the flat surface on the brace 17 and the flat surface on the side of the nut 24, which engages the screw-threaded end of the tie-rod. Before the lip 23 is brought into engagement with the nut, the nut is turned upon said 30 threaded part to force the brace and the gripping elements into firm engagement with the rail.

By the brace structure herein set out, there is provided a brace adapted to be adjusted to 35 rails of different height and size, due to the fact that the brace can move up and down and longitudinally of the tie-rod because of the peculiar nature of the opening through which the tie-rod passes.

40 While applicant has shown only one brace as applied to a rail, a similar brace may be applied to the outside part of each rail of the track. These braces are to be applied on the outside of the rail for the purpose of preventing 45 the spreading or turning of the rail, due to pressure on the inside of the head of the rail. These braces, while they are more particularly adapted and intended to be used on the outside of curves, may be used any place 50 where the rails need to be supported. By the use of devices of this kind, the rails are very firmly held, the pressure upon the spikes is greatly relieved, and the danger of wrecks from the rails spreading is materially lessened.

I desire to comprehend within my invention such modifications as may be clearly embraced within my claims and the scope of my invention.

55 Having thus fully described my invention, what I claim is new and desire to secure by Letters Patent, is:

1. In a railway rail brace, clamping means for said rails, said clamping means having a 60 projection thereon to act as a guide, a brace

means cooperating with said clamping means and engaging said guide for oblique motion in relation thereto for engaging the rail and bracing the rail, whereby strain is removed from the clamping means.

2. In a railway rail brace, clamping means 70 engaging the base of each rail, a guide on one of said clamping means, a brace means cooperating with said clamping means and guided upwardly by said guide to engage and brace the rail, and means cooperating with the clamping means and the guide means to firmly grip the parts to the rail and hold them in gripped relation.

3. In a railway rail brace, the combination 80 with a tie-rod, gripping means mounted upon said tie-rod and engaging the rail, said gripping means having a guide thereon, a brace means mounted upon said tie-rod and adapted to have a vertical and longitudinal motion thereon and having a groove therein to engage the guide, and means on the tie-rod for bringing the clamping means into engagement with the rail and the brace means into 85 engagement with the head of the rail.

4. In a railway rail brace, the combination 90 with a tie-rod, clamping means engaging the bases of said rails, guide means on said clamping means, brace means adapted to engage said tie-rod and guided by said guide means to engage the rail, means to hold the brace means in engagement with the clamping means and the rail and so constructed that pressure on the head-engaging part of the brace means tends to tilt the brace means and thereby force the gripping means into tighter gripping relation with the rail.

5. In a railway rail brace, the combination 100 with a tie-rod, means on said tie-rod to clamp both sides of the base of a rail, means on said tie-rod to clamp the outside base flange of a second rail, means cooperating with said second clamp means and having vertical and horizontal movements in relation thereto to engage under the head of the rail, and means 105 cooperating with said tie-rod to force all of said means into engagement with the rails.

6. In a railway rail brace, the combination 110 with a tie-rod, means on said tie-rod to clamp the outside of the base of a rail, means on said tie-rod to clamp the inside and outside base of a second rail, means cooperating with said outside clamping means of said second rail and having horizontal and vertical movements in relation thereto to engage under the head of said second rail, and means mounted on said tie-rod to force all of said means in 115 engagement with the rails.

7. In a railway rail brace, the combination 120 with a tie-rod, means on said tie-rod to engage the base of a rail, means on said tie-rod to clamp the outside base flange of a second rail, means cooperating with said second means adapted to move upwardly against the 125

5 rail to engage under the head of said second rail, and means mounted on said tie-rod to force the clamping means to grip the top, bottom and edge of said outside base flange of said second rail and to force the second means under the head of said second rail to keep the two rails in alignment and to prevent tilting.

10 8. In a railway brace, a tie-rod, a clamping member engaging each rail and having an opening to receive the tie-rod, a wedging member coacting with each clamping member to grip the rail and having an elongated opening to receive the tie-rod, brace means 15 having an elongated slot to receive the tie-rod in sliding engagement with one of the wedging members, and means to force the clamping members, the wedging members and the brace means into engagement with 20 each other to clamp and brace the rails.

25 9. In a railway rail brace, in combination with a tie rod, a clamping member on said tie rod adapted to extend under the base flange of a rail and engage the top thereof, 30 said clamping member having a guide extension thereon, a wedging sleeve on said tie rod and cooperating with said clamping member to grip a rail, said sleeve having a guide surface on one end thereof in a plane substantially parallel to a similar plane on the guide extension, and a rail brace in engagement with said guide surfaces to engage under the head of the rail.

35 In testimony whereof, I affix my signature.
JOHN G. MUELLER.
